UNITED STATES PATENT OFFICE.

ALBERT E. MAYNARD AND WILLIAM A. GUNNING, OF SOUTHBridge, MASSACHUSETTS, ASSIGNORS TO AMERICAN OPTICAL COMPANY, OF SOUTHBridge, MASSACHUSETTS, A VOLUNTARY ASSOCIATION OF MASSACHUSETTS.

EDGING MACHINE.

Application filed July 19, 1920. Serial No. 397,286.

To all whom it may concern:

Be it known that we, ALBERT E. MAYNARD and WILLIAM A. GUNNING, citizens of the United States, residing at Southbridge, in the county of Worcester and State of Massachusetts, have invented certain new and useful Improvements in Edging Machines, of which the following is a specification.

This invention relates to improvements in edging machines and has particular reference to a novel and improved construction of honing device for use in connection therewith.

One of the principal objects of the present invention is the provision of a novel and improved construction of hone particularly adapted for use in connection with that type of edging machines having a non-reciprocating stone, which hone shall be capable of being so shifted as to be used in truing up the stone from time to time as may be required.

A further object of the present invention is the provision in connection with a structure of this character, of improved means for preventing splashing of the water in which the stone runs about the machine and instead causing the return of the same to the original trough or container therefor.

Other objects and advantages of our improved construction should be readily apparent by reference to the following specification taken in connection with the accompanying drawings, and it will be understood that we may make any modifications in the specific details of construction shown and described within the scope of the appended claims without departing from or exceeding the spirit of our invention.

Figure I represents a side elevation of an edging machine embodying our improvements.

Figure II represents a fragmentary plan view thereof, particularly illustrating our improvements.

Figure III represents a sectional view taken as on the line III—III of Figure II.

In the drawings, the numeral 1 designates the base or tub of our edging machine, having journaled therein the shaft 2 for the

stone 3 which is suitably driven as by a belt passing around the pulley 4. It is to be understood that what we term an edging machine is a machine intended for use in grinding the edges of ophthalmic lenses, and the particular type of machine here illustrated is one which is especially intended for hand work, that is, in which no holder has been provided for the lens, which is manipulated by hand during the edging operation, although it will be understood that our improvement is equally applicable to other types of edging machines if desired. In any event, we have shown as formed on the rear of the tub the guide way 5, on which rests the transverse slide 6 having the undercut portions 7 interlocking with the dove tail rib or slide member 8 extending upwardly from the portion 5. This member 8 is centrally grooved as at 9 in order that the rack 10 secured on the under side of the member 6 may freely slide therethrough while meshing with the rack 10 is a worm 11 on the spindle or shaft 12. This shaft is rotatably mounted in the guide member 5 being held against longitudinal movement as by the washer 13 at one end and the collar 14 at the other, said collar 14 bearing the operating handle 15 which if desired may be provided with a crank 16 for rotating the spindle, the effect of this being that the meshing of the worm 11 and rack 10 will cause the slide 6 to be transversely shifted in desired relation to the stone 3. This slide 6 has mounted thereon a second cross slide 17 movable toward and away from the stone, having the guide portion 18 sliding in the guide way 19 of the slide 6, this in and out adjustment being controlled by the adjusting screw 20 which is threaded into the guide rib 18 and held to the slide 6 for rotation but against relative movement thereto in any well known or customary manner. This in and out adjustment, it will be understood, serves to control the pressure of the hone 21 against the edge of the stone 3 so that as the stone rotates the hone will bear thereagainst to keep the surface in proper condition. Should, however, the stone and hone become worn in other than correct relation 100

ship, or if desired to slightly true up the stone the hone may be moved back and forth across the stone or set at a new position to correct any slight surface errors, such as 5 tendency to groove. If, however, the surface of the stone becomes in really bad condition it is then necessary that the same be accurately trued up or resurfaced and this is ordinarily accomplished through the use 10 of what is known as a truing diamond, in which event the stone is preferably relegated to a secondary position and in its stead the truing diamond 22 is mounted in the diamond holder 23 on top of the stone holder 24, being secured in position as by the 15 set screw 25. Transverse back and forth movement of the slide 6 through rotation of the spindle 12 will then through worm and rack connection move the diamond back and forth across the face of the stone at a relatively slow rate, turning down the stone to proper shape and at the same time the pressure being controlled and the amount of surface removed regulated through rotation of 20 the screw 20 and thus in and out adjustment of the diamond holder and diamond.

To take care of the grit and water removed during truing, or to receive and lead away the water ordinarily on the surface of the stone and removed by the hone as the stone rotates, we preferably provide a trough member such as is illustrated at 26, disposed on the member 6 immediately adjacent the stone and beneath the hone 21 so that as the water strikes the hone and is deflected thereagainst and starts to drip downwardly in place of running over the sides of the machine it will run into the trough and be directed back onto the tub 1, protecting the machine from spattering and rusting or caking up through the splashing and dripping of the stone moistening fluid. This action may if desired be supplemented by forming a rim 27 around the hone holder 24, which also is shaped to drain toward the trough 26.

We claim:

1. The combination with a frame, of an edging machine, a stone surface honing device therefor, including a transversely adjustable slide, a second slide mounted on the first and adjustable in a direction at right angles thereto, said second slide comprising a holder member having a hone receiving socket formed centrally therein and having an upstanding apertured lug formed with a diamond shaft receiving socket, and means respectively designed to secure a hone and a diamond holder in their respective sockets.

2. The combination with a frame, of an edging machine, a stone surface honing device therefor, including a transversely adjustable slide, a second slide mounted on the

first and adjustable in a direction at right angles thereto, said second slide comprising a holder member having a hone receiving socket formed centrally therein and having an upstanding apertured lug formed with a diamond shaft receiving socket, and means respectively designed to secure a hone and a diamond holder in their respective sockets, said holder having a spaced upstanding flange formed on the body of the slide providing abradant fluid receiving channels to prevent said fluid flowing into and gobbing up or cutting out the slide-ways.

3. In a machine of the character described, the combination with a supporting portion having a groove formed therein and a recess in communication with the groove, of a worm rotatably mounted in the recess and projecting upward into the groove, a hone carrying slide mounted on the support and transversely shiftable thereover, said slide having a depending guide portion fitting within the groove and having a rack meshing with the worm for affording transverse adjustment of the hone slide.

4. A combined honing and truing attachment for an edging machine comprising a pair of slides adjustable at right angles one to the other, means for supporting the slides adjacent the periphery of the stone, and a combined hone and truing device holder mounted on the uppermost slide whereby said combined holder may be moved in the direction of and transversely with respect to the edge of the stone to produce and maintain the desired trued surface thereon.

5. A device of the character described including a hone holder having an upstanding flange forming a drip receiving groove around the hone holder, and a supplemental trough disposed beneath the holder and groove for directing the drip therefrom.

6. An edging machine including a tub, a stone rotatably mounted therein, a slide mounted on the tub adjacent the edge of the stone, a rack mechanism for transversely shifting the slide, a cross slide mounted on the first slide, means for adjusting the cross slide in the direction of the stone, a hone holder mounted on the slide, said slides being formed with cooperating drip receiving grooves to return to the tub abrasive and fluid removed from the surface of the stone by the hone.

In testimony whereof we have affixed our signatures, in presence of two witnesses.

ALBERT E. MAYNARD.
WILLIAM A. GUNNING.
